UNITED STATES PATENT OFFICE.

DOLPHAS D. PALMER, OF WALTHAM, MASSACHUSETTS.

STEM-WINDING MECHANISM FOR WATCHES.

SPECIFICATION forming part of Letters Patent No. 272,310, dated February 13, 1883.

Application filed June 10, 1882. (Model.)

To all whom it may concern:

Be it known that I, DOLPHAS D. PALMER, of Waltham, county of Middlesex, State of Massachusetts, have invented an Improvement in Watches, of which the following description, in connection with the accompanying drawings, is a specification.

My invention relates to improvements in, and has for its object to simplify, the stem winding and setting mechanism. I have devised and employ a crown-gear having a movable fulcrum, which, when held in its normal condition, causes the toothed periphery of the crown-gear thereon to engage the usual winding-gear on the spindle, which winds the usual driving-spring. When it is desired to set the hands the fulcrum of the crown-gear is shifted so as to disengage the toothed periphery of the crown-gear from the said winding-gear and engage it with the first gear of the setting-train. As herein shown, I have provided the rotating longitudinally-movable stem with a cam or shoulder, which I have made available as the means for moving the fulcrum of the crown-gear in one direction, a spring moving it in the other direction.

Figure 1 represents one side of the center-plate of a watch-movement; Fig. 2, a view of the opposite side of the said plate, with the usual spring-barrel broken away at one side and the plate broken away near one edge; Fig. 3, a section of the shield and movable fulcrum for the crown-gear. Fig. 4 is an inner side view of the shield. Fig. 5 is a view of one side of the movable fulcrum with the crown-gear thereon; Fig. 6, a view of the under side of the parts shown in Fig. 5, and Fig. 7 is a section of the winding-stem and its bevel-pinion.

The center plate, a , is that which is fitted into the central part of the watch-frame and holds on one or the other of its sides the different movable parts.

The winding-stem a' , having a milled head, a^2 , has its shank held in the bearing a^3 by the end of a screw, a^4 , which enters an annular groove in the said shank, the said groove being enough wider than the point or end of the said screw to permit the stem to be moved longitudinally for a little distance, as well as to be rotated. The inner end of this stem a'

is squared, as shown, to fit a square opening at the center of the bevel-pinion a^5 , the periphery of which at one side is placed loosely in a notch in the center plate, while stem of the said pinion is extended into the bearing a^6 . (See Fig. 7.) The pinion is free to turn with the stem a' , but cannot move with the said stem longitudinally.

The usual barrel, b , within which is placed the driving-spring, (not shown,) is broken away in Fig. 2 to show the winding-gear b' below it, the said winding-gear being secured to the shaft b^2 , with which will be connected the usual driving-spring of the watch mechanism. This winding-gear is prevented from rotating in the wrong direction by means of the detent b^3 , pivoted at b^4 in a recess in plate a , and acted upon by a spiral spring, b^5 , placed in a pocket or hole drilled into the edge of the center plate, as in Fig. 2.

Prior to my invention this detent has always been acted upon by a long flat spring, which was exposed, and was very expensive as compared with the small spiral spring, which is effectually held against damage or loss in the said pocket, the pocket and spring being much cheaper than the usual flat spring, and being easier and quicker to apply.

The gear c on stud c' is the first gear of the setting-train. It will in practice engage another gear on the stud c^2 , which will, in the usual manner, turn the setting-train to move the hands of the watch, the most of the said setting-train being omitted because not of my invention.

The under side of the bearing a^6 , which holds the shank of the bevel-pinion a^5 and end of stem a' , has secured to it by screw 2 (see Fig. 1) a small shield, d , which, at its inner side, (see Fig. 4,) is chambered at 4 to receive the movable fulcrum d' , having a projecting portion, d^2 , provided with an eye, 5, (see Figs. 5 and 6,) which is placed on an annular projection, d^3 , forming part of the shield d . The shield d , with its fulcrum d' and crown-gear, is fitted in the recess a^7 , Fig. 7, the screw 2, Fig. 1, serving to hold the same in place by entering the block a^6 . The central portion of this fulcrum and the flange about it receives the crown-gear e , herein made as an annulus having peripheral and side teeth.

- The chamber 4 in the shield is enough larger than the fulcrum d' to allow the same to be moved therein for a short distance laterally, or in an arc of a circle about the projection d^3 .
- 5 The movable fulcrum d' has fixed to and projecting from one side of it a pin or stud, 3, (see Fig. 5,) which is extended through an opening in the center-plate a , as in Fig. 2, so as to be struck by the shoulder or cam-projection 8 of the stem a' . This stem a' is grooved annularly to produce the shoulder or cam 8, and a spring, f , held by screw f' , acts against this stud 3 to keep the same normally pressed toward the axis of the stem a' . When the stem 15 a' is pushed in, which is its normal position, the stud 3 rests in the annular groove of the stem, as in Fig. 2, and the peripheral teeth of the crown-gear engage the teeth of the winding-gear b' , ready to wind the driving-spring 20 of the watch.
- When it is desired to move the hands to set the watch, or to move the setting-train of gearing, it is necessary only to pull the stem out, as indicated by dotted lines, Fig. 1, when the shoulder 8 acts on the stud 3, forces it aside, and with it the fulcrum d' , which causes it to place the peripheral teeth of the crown-gear into engagement with the first gear, c , of the setting-train, when rotation of the stem a' will cause 25 the bevel-pinion a^5 , always in engagement with the face or side teeth of the crown-gear e , to turn the said crown-gear, and the latter to turn the gear c . By means of the shoulder on the stem a' and the spring f , the fulcrum 30 d' may be moved sufficiently far in either direction to enable the crown-gear to be thrown at will into engagement with and so as to rotate either the gear b' to wind the watch or the gear c to set the watch.
- 35 In this my invention I make one and the same gear—namely, the crown-gear—the common motor for the winding and setting mechanisms, thus avoiding, as heretofore, the employment of two separate gears to engage and move the said mechanisms, and also avoiding complicated levers and springs to hold the said gears.
- 40 Parts not herein shown will be as common in other watches.
- 45 The crown-gear in Fig. 1 is shown by dotted lines as in engagement with the gear c of the setting-train, as will be the case when the stem a' is pulled out, as shown by dotted lines.

The end of the part d^3 of the shield rests directly against the block a^6 , so that the eyed part d^2 of the movable fulcrum d' is free to be easily moved by the stem a' .

I claim—

1. The gear b' , forming part of the winding mechanism, and the gear c , forming part of the 60 setting train or mechanism, combined with the movable fulcrum and the crown-gear carried by and moving with said fulcrum, whereby, by change of position of the said fulcrum, the said crown-gear may be made to engage the 65 gear b' or the gear c to wind or to set the watch, respectively, as desired, substantially as described.

2. The stem a' , squared at its end and having its bearings secured to the center plate, a , 70 and the beveled pinion a^5 , in which the said stem may slide longitudinally, combined with the crown-gear and movable fulcrum d' , substantially as and for the purpose set forth.

3. The longitudinally-movable stem a' , provided with shoulder 8, the pinion a^5 , and crown-gear, combined with the movable fulcrum to support the crown-gear, and the stud 3 thereon, acted upon by the said shoulder, to operate 75 substantially as described.

4. The longitudinally-movable stem a' , provided with the shoulder 8, the spring f , the pinion a^5 , and the fulcrum and its stud 3, combined with the gear b' , gear c , and crown-gear arranged between the said gear b' and gear c , 80 to engage and turn either one, as may be desired, substantially as described.

5. The gear b' of the winding mechanism, and its detent b^3 , combined with the spiral spring b^5 , inclosed in a pocket or opening made 90 in the center plate, all substantially as shown and described.

6. The shield provided with portion d^3 , the bearing-block a^6 , with which the said shield is connected by screw, and movable fulcrum 95 provided with a projecting portion, d^2 , having an eye to fit the portion d^3 , combined with the crown-gear and stem a' , substantially as described.

In testimony whereof I have signed my name 100 to this specification in the presence of two subscribing witnesses.

DOLPHAS D. PALMER.
